WALTER CLINT DAYTON, OF BUFFALO, NEW YORK, ASSIGNOR TO GEORGE H. SMITH, TRUSTEE, OF BUFFALO, NEW YORK.

PROCESS AND APPARATUS FOR REMOVING TAR AND OTHER CONDENSABLES FROM GAS.

1,200,442.

Specification of Letters Patent.

Patented Oct. 3, 1916.

Application filed February 5, 1914. Serial No. 816,763.

To all whom it may concern:

Be it known that I, WALTER CLINT DAYTON, a citizen of the United States, residing at Buffalo, in the county of Erie and State of New York, have invented certain new and useful Improvements in Processes and Apparatus for Removing Tar and other Condensables from Gas, of which the following is a specification.

10 My invention relates to a process and apparatus for removing tar and other condensables from gas.

I shall hereinafter employ the term tar, both in the specifications and in the claims, 15 as indicating all forms of condensables which it is desirable to remove by my process and apparatus.

In the manufacture of gas from liquid hydrocarbons it has been especially difficult 20 to free the gas from tar so that the gas can be used generally, and the same condition has prevailed, relatively speaking, in the manufacture of gas from other forms of hydrocarbon.

25 I have discovered that, when a tar-laden gas is compressed slightly and then permitted to expand, a certain amount of tar is deposited adjacent to the point of expansion. From this discovery and by 30 further experiment and operation, I have found that, if such gas is expanded, then compressed, and finally permitted to escape through a restricted opening into a chamber and conveyed from that chamber, by proper 35 conditions such as I shall hereafter point out, practically all of the tar will be precipitated in such chamber and the gas left substantially pure.

The concrete side of my discovery will be 40 better understood from a description of my novel apparatus for carrying out my process and the method of its operation; but it is to be understood that my process is not limited to any specific form of apparatus.

45 Referring to the single figure of the drawing herewith, which is a vertical section, 1 is a pump cylinder within which a piston 2 reciprocates. The pump may be driven from any desired source of power, as 50 by a driven shaft 3 rotating a crank-disk 4 pivoted to the connecting-rod 5.

Surrounding the cylinder 1 is an annular chamber 6 into which a gas main 7 leads the supply of tar-laden gas. An annular

port 8 leads from the chamber 6 into the cylinder 1, which port is uncovered by the piston 2 as it reaches the limit of its out-stroke. This annular port may be bridged to permit free passage of piston-rings or may be otherwise formed—the preferable construction being that it shall be large in cross-section, that the chamber 6 shall be of substantial size and that the port be opened and closed when the piston is traveling at minimum stroke-speed.

Instead of an ordinary fixed head, the cylinder 1 is provided with a valve 9, which is disk-shaped and sets down upon the end flange of the cylinder, a packing 10 being interposed to make a gas-tight joint when the valve is closed. The stem 11 of the valve 9 reciprocates in a central boring 12 in an adjustable sleeve 13 which is threaded into the casing 14 of the chamber 15. A compression spring 16 is interposed between the valve 9 and an annular seat on the sleeve 13 and this spring tends to hold the valve 9 seated against gas pressure within the cylinder; and as the sleeve 13 is adjustable, the compression spring 16 may be regulated with the result that the degree of gas pressure in the cylinder which will unseat the valve may be accurately determined. To prevent vacuum or pressure in the boring 12 the stem 11 has a central boring 22 which leads out to the gas area of the chamber 15. A pipe 17 leads from the chamber 15 to any desired point of storage or use of the clean gas.

Below and opening into the chamber 15 is an annular chamber 18, about the cylinder 1, which is separated from the chamber 6 by the wall or partition 19. Leading from the chamber 18 close to its floor is a pipe 20 which leads into a tar container 21, or which may be sealed against gas-flow in any well-known manner.

The operation is as follows: A supply of tar-laden gas being conveyed into the chamber 6 from the pipe 7 and the pump started, when the piston 2 makes its outstroke producing the usual partial vacuum in the cylinder 1 and uncovering the annular port 8, gas is drawn into the cylinder from the chamber 6 with accompanying expansion into the partial vacuum. When the piston makes the in-stroke it compresses the gas contained within the cylinder with the re-

- sult that the tar particles are brought into closer relation and agglomeration or increase of size of particles follows and the temperature is raised slightly. The pressure for 5 successful operation with the gas of the quality and kind I have used should be about four pounds to the square inch, but the pressure should be regulated according to the nature and content of any gas being treated.
- 10 As the piston compresses the gas to the pre-determined degree—determined by the adjustment of the sleeve 13 upon the spring 16—the valve 9 is raised slightly and the gas escapes through the shallow, restricted, annular space between the packing 10 and the head flange of the cylinder 1; and this escape continues during the remainder of the in-stroke of the piston 2. The action of this 15 escape of the gas through this annular, narrow slit causes further combination or agglomeration of the tar particles; and as the gas, thus somewhat heated, escapes into the chamber 15, a cooling or refrigeration of the gas due to expansion takes place as it 20 leaves this annular slit and the tar particles precipitate or settle into the chamber 18. The cleaned gas passes up through the pipe 17 and the tar flows from the chamber 18 through the pipe 20 to the tar container 21.
- 25 While the apparatus shown and described is novel and best adapted to carrying out my process of any apparatus known to me, it is to be understood that my process may be carried out by other apparatus.
- 30 Having thus described my invention and discovery, I claim:
1. The process of cleaning gas which consists in expanding the gas to be cleaned to cause a precipitation of easily condensable 35 materials, compressing the gas, expanding the compressed gas through an opening of such dimensions as to cause agglomeration of the tar particles, permitting the tar particles to settle from the gas, and conducting 40 away the cleaned gas.
2. An apparatus for cleaning gas containing liquid or solid matter comprising the combination of means for expanding the gas to be cleaned and subsequently compressing 45 the same, means permitting expansion of the compressed gas through a slit like orifice of such dimensions as to cause agglomeration of the tar particles, an expansion chamber for receiving the gas permitting settling of 50 precipitated matter, and means for conveying away the cleaned gas.
3. An apparatus for cleaning gas containing tar comprising the combination of a cylinder, a piston therefor, a duct at one end 55 of the cylinder for admitting the gas when 60 a vacuum has been produced in said cylinder by an outward stroke of the piston, means for automatically opening a narrow slit at the opposite end of the cylinder when the admitted gas has been compressed to a pre- 65 determined pressure, an expansion chamber for receiving the expanding gas, a tar-receiving chamber below said slit, and an upwardly extending duct conducting the cleaned gas in a direction away from the 70 tar-receiving chamber.
4. An apparatus for cleaning gas containing impurities condensable at ordinary temperatures, comprising the combination of a cylinder, a piston reciprocating therein, 75 means for expanding the gas to be cleaned into said cylinder when a partial vacuum has been produced therein, a valve for causing the gas to be discharged through a restricted slit-like orifice when compressed to 80 a predetermined degree, a settling chamber for collecting precipitated non-gaseous matter, and a conduit for conveying away the cleaned gas.
5. An apparatus for cleaning gas comprising a cylinder having a head movable to open a narrow orifice, a piston reciprocating therein, ports for admitting gas uncovered by said piston near the limit of its outward stroke after producing a partial vacuum in said cylinder, a regulatable pressure device acting to hold closed the head of said cylinder until the pressure of gas reaches a predetermined value, an expansion chamber for receiving gas from the cylinder through 90 an orifice between the cylinder and the movable head, a conduit for conveying away cleaned gas and a conduit for carrying away precipitated non-gaseous matter.
6. An apparatus for cleaning gas containing suspended tar particles comprising a container, means for admitting gas to be cleaned to said container, an expansion chamber for receiving gas from the container, means for conveying gas into the expansion chamber through a narrow slit of 95 such dimensions that the tar particles in the gas will be agglomerated, a conduit for conveying away the cleaned gas, and means for collecting and conveying away precipitated 100 tarry material.
- 105 In testimony that I claim the foregoing invention I have hereunto set my hand in the presence of two witnesses.

WALTER CLINT DAYTON.
